A. W. Cheever,

Shoe Last,

No 67,414,

Patented Aug. 6, 1867.

United States Patent Office.

AARON W. CHEEVER, OF LYNN, MASSACHUSETTS.

Letters Patent No. 67,414, dated August 6, 1867.

IMPROVEMENT IN LASTS.

The Schedule referred to in these Letters Patent and making part of the same.

TO ALL WHOM IT MAY CONCERN:

Be it known that I, AARON W. CHEEVER, of Lynn, in the county of Essex, and State of Massachusetts, have invented certain Improvements in Lasts, of which the following is a full, clear, and exact description, reference being had to the accompanying drawings, making part of this specification, in which—

Figure 1 is a perspective view of one of my improved lasts.

Figure 2 is a longitudinal vertical section through the centre of the same.

Figure 3 is a section taken in the plane of the "draught line" of the last.

Figure 4 is a transverse vertical section on the line $x\ x$ of fig. 2.

Figure 5 is a transverse vertical section on the line $y\ y$ of fig. 2.

Figure 6 is a longitudinal section through one of my improved lasts with an extreme hollow to the shank.

To produce a boot or shoe in which the "draught line" will be preserved in any of the positions naturally assumed by the wearer, it is necessary to employ a last of the exact form of a perfect foot of the size of the boot or shoe required; but the experiments heretofore made to arrive at this desired form have only been approximately successful.

My invention particularly relates to that class of lasts which are made in two pieces, *i. e.*, the "last proper," or lower piece, and the "block" placed upon it; and my invention consists in so shaping the last and its "block" that the length of a horizontal line measured across the last in a plane passing through or a little below the "draught line," at any point forward of the instep, and also at its rear over the shank, will be greater than the corresponding line (thus measured) in lasts as heretofore made, while the sectional area through the last, at the given point measured, in a plane at right angles to the draught line remains the same, and I obtain the requisite amount of "fullness" without the wrinkling of the boot or shoe occasioned by the draught line being thrown out of place in walking incident to lasts of the ordinary construction.

My invention also consists in making the "draught line" straight on the exterior surface of the last from a point near the heel to a point at the "ball;" and my invention also consists in forming a projection at the toe end of the "block" of the last, and also in certain improvements in the construction of the groove in the "last proper" and in the tongue on the "block," which slides therein for a purpose to be explained hereafter; and my invention furthermore consists in increasing the height of the instep without increasing the length of the "heel line" to produce a boot or shoe with an extremely hollowing shank.

To enable others skilled in the art to understand and use my invention, I will proceed to describe the manner in which I have carried it out.

In the said drawings, A is the "last proper," provided with a groove, *a*, in which slides a dove-tailed strip or tongue piece, *b*, screwed or otherwise fastened or formed on the under side of the block B. Z Z is the "draught line," (seen in red, figs. 1, 2, and 6,) the position of which is ordinarily determined by last-makers by drawing a line on the exterior of the last from the highest point in the curve of the heel to the toe. A line passing through these points is the direction assumed by the human foot in its natural positions, whether in motion or at rest, this draught line being the resultant of the directions of the forces exerted by the various muscles and cords. With my improved last the horizontal distance from any point *c* on one side of the last to a point, *d*, on its opposite side, measured on or a little below the plane of the draught line, is greater than a corresponding line in a last of the old construction, while the amount of "fullness" remains the same in my last as in a common last of the same size, the shape of the last measured transversely across it (as shown in section fig. 4) being the best upon which to crimp or mould the "upper" to insure it fitting the foot perfectly in this direction. A portion of the draught line, (measured on the exterior side surface of the last,) from a point, *e*, near the heel to a point, *f*, at the "ball," is straight, the remaining portion of the draught line between these points and the toe and heel respectively being of a gradual curvature, by which construction, in connection with its transverse sectional area, a last will be produced upon which a boot or shoe may be made that will smoothly and snugly adapt itself to the conformation of the foot without playing up and down thereon, and without wrinkling the "upper" incident to a boot or shoe made on an old pattern of last. *g* is a projection formed on the upper side of the toe end of the block B, in order to give more "fullness" at this point, and thus avoid the toes being pinched or chafed. A similar projection for the same purpose has been formed on

the "last proper," but when several boots or shoes of different "fullness" are required, where such lasts are employed, it becomes necessary to furnish an entire last for each separate pattern; whereas my improved "block last" enables me to use the same "last proper" for different degrees of fullness, and only necessitates the "block" being changed, by which means a considerable saving is effected in the construction of lasts.

In the operation of lasting a boot or shoe, or when "beating out the bottom," or re-lasting upon a last of the old construction, the "upper" was frequently wrinkled and damaged by being pinched between the "last proper" and its block, which liability does not exist where a block of my improved construction is employed, as the toe is formed thereon, and no joint occurs in which to pinch the "upper," and the block being prevented by its projection *g* from working in the "upper," the desired shape and fullness of the boot or shoe is obtained. The width across that portion of a last of the old construction in which the groove is formed for the reception of the dove-tailed portion of the block is narrow, owing to the peculiar form of the last and rapid inclination of the line upon which the block slides, and consequently the amount of material at this point is only sufficient to make a narrow groove, but the length of the groove has been increased to retain the block properly upon its last.

This construction is, however, objectionable, on account of the difficulty of removing the block from the last when they are within the boot or shoe, the upper or instep end of the block coming in contact with the leg of the boot or shoe, whereby the dove-tailed strip is frequently broken. But with my improvements the surface of the "last proper," on which the block slides, is wider, and a wider groove can consequently be formed therein without weakening the former, and thus the length of the groove may be diminished, by which construction the block can be readily removed from its last without interfering with the leg of the boot or shoe, and the liability of splitting the dove-tailed strip is avoided.

In fig. 6 is represented one of my improved lasts, in which the height of the instep from 7 to 8 is increased without increasing the length of the "heel line" from 9 to 10. This result is accomplished by adding to the top or instep portion of the block what is cut out from the bottom or shank portion of the last, the amount added to the instep being placed entirely forward of and nearly level with the point 9.

The object of this construction is simply to please the fancy of the wearer, and as frequent inquiries are made for a boot or shoe that "looks well on the foot" the shank is therefore made extremely hollowing.

Claim.

What I claim as my invention, and desire to secure by Letters Patent, is—

The "block last" A B, constructed substantially as above described and for the purpose set forth.

I also claim making the "draught line" straight on the exterior surface of the last from a point near the heel to a point at the "ball" of the foot, substantially as and for the purpose set forth.

I also claim forming a projection, *g*, on the toe end of the "block" of the last, substantially as and for the purpose described.

I also claim increasing the width and reducing the length of the groove in the "last proper," as and for the purpose specified.

AARON W. CHEEVER.
